UNITED STATES PATENT OFFICE

168,857

DENTAL CHAIR OR THE LIKE

Edward J. Ries, Brighton, N. Y., assignor to Ritter Company, Inc., Rochester, N. Y., a corporation of Delaware

Application October 6, 1952, Serial No. 21,709

Term of patent 14 years

(Cl. D15—3)

To all whom it may concern:

Be it known that I, Edward J. Ries, a citizen of the United States of America, residing at Brighton, in the county of Monroe and State of New York, have invented a new, original, and ornamental Design for a Dental Chair or the like, of which the following is a specification, reference being had to the accompanying drawings, forming part thereof, in which

Fig. 1 is a side perspective view of a dental chair or the like, showing my new design;

Fig. 2 is a front perspective view thereof.

The characteristic feature of the design resides in the solid line portion.

I claim:

The ornamental design for a dental chair or the like, substantially as shown and described.

EDWARD J. RIES.
